SAFETY RAZOR

Sidney H. Benjamin, Milwaukee, Wis.

Application March 20, 1935, Serial No. 11,970

16 Claims.

(Cl. 30—47)

My invention relates to safety razors and refers particularly to that type of razor in which the razor head, or extra blades therefor, or both, are capable of being stored and housed within a 5 tubular razor handle.

In this respect, as well as in others, my invention is a further development of an improvement over the safety razor of this type which is disclosed and claimed in Patent No. 1,924,641, 10 granted August 29, 1933, to Auguste Dupeyron.

Among the objects of my invention are to provide for a more convenient manipulation of the razor head and its reserve supply of blades and also to provide greater protection for the housed 15 extra blades. Another object of my invention is to strengthen and stiffen the razor head, especially the guard element thereof. Other objects and advantages will hereinafter become evident.

20 In carrying out my invention, special protection is provided for the exposed edges of a blade mounted in the assembled housed razor head. A suitable blade carrier is provided which is adapted to contain a desirable number of packages 25 of extra blades. Means are provided by which this blade carrier, together with its contained blade packages, and the razor head may be conveniently integrated into a compact unitary assemblage, with the individual parts of such assemblage all positively positioned relatively to each other.

The mentioned assemblage is removably and replaceably receivable within a tubular handle member. This handle member is of the usual 35 length and diameter of safety razor handles, with the mentioned assemblage of parts snugly but easily and conveniently slidably therein, and adapted to be maintained in assembled relation thereby.

40 More particularly, in carrying out my invention, the usual screw-threaded stem of the cap member of the head, which passes centrally through the mounted razor blade and the guard therefor, also is capable of being passed centrally through the blade carrier and packaged blades contained therein, thereby to position the blade carrier and packaged blades upon the assembled detached razor head.

45 This blade carrier is of elongated flattened box-like construction and is positioned upon the razor head by means of the mentioned cap stud. The sliding fit of this unitary assemblage of parts within the tubular handle is sufficiently snug to 50 maintain their assembled condition. A remov-

able and replaceable outer end closure for the tubular handle retains this assemblage therein.

The mentioned stiffening of the guard member is effected by eliminating all openings through it with the single exception of a central opening 5 through which the mentioned cap stud passes for connecting the head as a whole to the end of the tubular handle at its end opposite to the mentioned end closure. Also, this guard member is further stiffened by providing aligning lugs for 10 the blade and cap member upon the guard member.

These mentioned lugs pass through the blade and into an inner longitudinal groove formed in the under side of the cap member of the head. 15 This cap member is so shaped as to secure desirable longitudinal rigidity, being substantially trough-shaped, with a substantially V-shaped outer side surface.

These stiffened razor head parts are dimensioned, shaped and proportioned for the most effective cooperation of the mentioned assemblage with the housing chamber of the tubular handle member, and for protecting the blade in the assembled razor head when thus housed. 20

My invention further includes various features of construction and combinations of parts, as will be evident from the following particular description taken in connection with the accompanying drawing illustrating one form of my invention, with modified forms of some parts, and in which similar parts are designated by similar numerals. 25

Figure 1 is a full size elevation partly in section of a safety razor embodying my invention. 35

Figure 2 is an enlarged broken elevation as viewed at right angles in Figure 1.

Figure 3 is a similarly enlarged plan view from above in Figure 1.

Figure 4 is a broken vertical section on the line 40 4—4 of Figure 3.

Figure 5 is a much enlarged broken vertical section on the line 5—5 of Figure 4.

Figure 6 is an enlarged elevation of the cap element of the razor head as viewed in Figures 45 1 and 4.

Figure 7 is an inverted plan view of this cap element.

Figure 8 is a plan view of the guard element.

Figure 9 is a plan view of a razor blade. 50

Figure 10 is a perspective plan view of a blade carrier for reserve blade packages, this carrier being shown as empty.

Figure 11 is a somewhat further enlarged transverse section of the tubular handle, shown as 55

housing therein an assembly of the razor head with the razor blade carrier, the latter having a reserve supply of packaged blades therein.

Figure 12 is an enlarged central longitudinal section transversely of the width of a modified form of the razor blade carrier.

Figure 13 is a moderately enlarged view similar to Figure 4, of a modification.

Figure 14 is an elevation as viewed from an end of Figure 13.

The particular form of the safety razor of my invention illustrated in Figures 1 and 2 to 11 inclusive, in the accompanying drawing, includes a handle member 20 of suitable length and diameter for conveniently and comfortably holding in the hand in the use of the device. This handle member is tubular and is shown as being octagonal in cross section, both externally and internally, although it could as well be externally round, or internally circular, or of circular, or other, cross section in both of these respects, if so desired.

The outer or free end of this tubular handle is adapted to be closed or opened by means of an outwardly shouldered or headed screw plug closure 21. The other end of this handle member 20 is adapted to carry the razor head and is shown as permanently closed by means of a solid taperingly reduced portion 22 which is shown as formed integrally or in one piece with the main tubular portion 20. The end of this tapered closure 22 has therein a screw-threaded socket-forming bore 23 by means of which this end of the handle is adapted to be removably and replaceably attached to the razor head, as will be described later.

The razor head is of the commonly usual length but is somewhat narrower than the internal diameter of the tubular handle member 20, as well as being of somewhat less length than the longitudinal depth of the chamber formed in this tubular handle between its removable closure plug 21 and its other end closure 22. This provides for housing the entire assembled head, together with a reserve supply of extra razor blades, contained in a blade carrier adapted to be assembled with the head, within the mentioned internal chamber of the tubular handle member 20, as will be described later.

The razor head comprises a guard element or member 24 and an outer cap element or member 25 together with an interposed razor blade 26 which the guard element 24 and the cap element 25 are adapted to retain in place in proper position for use.

The guard element 24 is shown as having a flat under surface and is notched along its opposite margins to provide two similar series of substantially usual outwardly rounded guard teeth 27-27, of which the terminal teeth are shown as being somewhat wider, as is usual. This guard element has through it centrally a longitudinally slotted aperture 28. The outer surface of this guard element 24, between its teeth 27-27, is transversely convex, or rounded. Two pairs of lugs 29-29 and 30-30 project to a suitable extent from this outer transversely rounded surface of the guard element 24.

These lugs are all of the same transverse width and are arranged in a longitudinal series along the guard element 24 in alignment with one another and with the central aperture 28. The lugs 29-29 of the intermediate pair are shown as longitudinally elongated and as suitably spaced respectively from the opposite ends of the simi-

larly elongated aperture 28. The lugs 30-30 of the terminal pair, which are interposed in spaced relation, respectively between the lugs 29-29 and the opposite ends of the guard element 24, are shown as of less length longitudinally of this guard element than the lugs 29-29. The purpose of these lugs will be described later.

The razor blade 26 has through it a longitudinal series of aligned apertures 31, 32-32, and 33-33, respectively corresponding to and adapted to register with the aperture 28, lugs 29-29, and lugs 30-30, of the guard element 24.

The cap element 25 is outwardly V-shaped in cross section and is provided longitudinally along its under or inner side with a right-angled groove 34 which is relatively wide and of less depth. The marginal edge portions of this cap element 25 flare outwardly at its under side away from the groove 34 at rather flat obtuse angles to each other and terminate laterally in rather acute-angled opposite edges. This groove 34 is interrupted midway of its length by an inwardly projecting lug 35 which projects inwardly beyond this groove to a greater extent than the mentioned pairs of lugs 29-29 and 30-30 project outwardly from the outer face of the guard member 24.

This inwardly projecting lug 35 is complementary to and adapted to register with the central aperture 31 of the blade 26, through which it is adapted to pass, and is likewise complementary to and adapted to register with the central aperture 28 through the guard element 24 into which this lug 35 is adapted to enter to a variable extent, without necessarily passing all of the way through to the flat under-side face of this guard element.

The lugs 29-29 and 30-30 of the guard element 24 are respectively adapted to register with and pass outwardly through the apertures 32-32 and 33-33 of the blade 26. These lugs 29-29 and 30-30 are transversely rectangular and have a readily removable fit between the side walls of the groove 24 in the cap element 25, without the flat ends of these lugs necessarily being at all times brought into abutment with the flat bottom of the groove 34.

The flat inner end of the cap element lug 35 rigidly carries an inwardly projecting screw-threaded stud or stem 36 of less length than the depth of the screw-threaded socket 23 in the tapered inner end portion 22 of the tubular handle member 20. The stud 36 is adapted to have screw-threaded engagement in the socket 23.

When the socket 23 and the stud 36 are screwed together, the transversely flat end of the tapered handle end portion 22 will be brought into abutment with the flat under face of the guard element 24, so that thereby the underlying guard element 24 and the outer cap element 25 can then be drawn toward each other upon the interposed longitudinally apertured blade 26. It is evident that thus this blade can be transversely bent or flexed to the proper extent for the most effective use.

The mentioned lugs 29-29 and 30-30 on the guard element 24 maintain this guard element and the cap element 25 and the razor blade 26 in alignment with each other, and also contribute to the rigidity of the guard element 24, which is stiffened by reason of having no openings through it other than its central aperture 28. The cap element 25 is stiffened by reason of its mentioned deep V-shape. This construction pre-

vents objectionable longitudinal bending of either the guard element 24 or the cap element 25, as well as of the razor blade 26, when these guard and cap elements are drawn together upon the 5 interposed blade.

10 Inturned end flanges 37-37, carried respectively by the opposite ends of the cap element 25, serve as end guards for the razor head and also constitute convenient finger grips in assembling and disassembling the described connected separable parts of the device. Also, as 15 end covers, they contribute to the ornamental appearance.

An elongated flattened blade carrier is formed 15 from suitable resilient sheet metal and is shown in Figures 10 and 11. As will be there noted, this blade carrier is substantially C-shaped in cross section transversely of its width and thickness and, as a whole, it is in general rectangular. 20 It has a flat back wall 38 provided with a central circular aperture 39, of as great a diameter as the cap stud 36, narrow forwardly-turned side walls 40-40, inturned opposed spaced front flanges 41-41 parallel with the back wall 38, and 25 a forwardly-turned end closure flange 42 at one of its ends only and which extends from the back 38 out to the front flanges 41-41.

The width of the guard element 24 between the 30 ends of its teeth 27-27, and the width of this blade carrier between the outer faces of its side walls 40-40, are shown as being the same. Also the length of the blade carrier is substantially the same as that of the guard element 24. The 35 width of the space between the opposed edges of the front flanges 41-41 of the blade carrier is shown as being slightly greater than the diameter of the hole 39 through the rear wall 38.

This blade carrier is of an internal width between the opposed inner faces of its side walls 40-40, and of a thickness or depth between the inner face of its rear wall 38 and the inner faces of the front flanges 41-41, to be adapted to receive therein a suitable predetermined number of blade-containing packages 43-43, shown 40 in Figure 11 as being six in number.

45 Each of these blade packages 43-43 contains a single razor blade, similar to the blade 26, which is enclosed and covered by a usual protecting paper wrapper, in accordance with the usual common practice, which is so well known as not to require special illustration and specific description. Each of these wrappers at each side of its enclosed blade is to be provided with a central opening in alignment with the central opening 31 in the blade 26 and also in alignment with the aperture 39 through the rear wall 38 of the 50 blade carrier, as is clearly indicated in Figure 11.

It is now evident that the razor head as a 55 whole, comprising the guard element 24, cap element 25 and blade 26, may be quickly and conveniently removed from the handle member 20 and reattached thereto. When the razor head has been thus removed, then the described blade carrier, together with its contained reserve blade packages 43-43, may be mounted upon the assembled razor head merely by passing the stud 36 of the latter through the hole 39 provided for it in the rear wall 38 of the blade carrier, similarly through the central openings in the blade packages 43-43, and out between the spaced front flanges 41-41 of the blade carrier, as clearly shown in Figure 11.

It is obvious that if desired, the stud 36 may be passed first between the blade carrier flange 75 41-41, through the blade packages 43-43, and

finally out through the hole 39 in the back wall 38 of the blade carrier. In the first instance, the rear wall 38 will rest flatly against and substantially cover the flat face of the guard element 24, while in the second instance the outer faces of the blade carrier front flanges 41-41 will be similarly disposed against the flat face of the guard element 24.

It is evident from Figure 11 that the stud 36 will now function to prevent any relative sliding 10 movement in any direction between the blade carrier and the assembled head elements, including the guard element 24, while at the same time this stud 36 will lock the blade packages 15 43-43 in the blade carrier and prevent their escape therefrom or movement therein.

The described unitary assemblage of razor head parts, blade carrier and blade packages, may now be readily slid longitudinally into the outer open end of the tubular handle 20 after the closure 20 plug 21 of the latter has been removed and then this closure plug may be replaced upon the tubular handle for securely retaining the described assemblage therein.

This housed assemblage has only very slight 25 transverse or lateral looseness within the closed chamber thus formed within the tubular handle 20 and not very much play therein longitudinally. The transverse fit of this assemblage of parts within the tubular handle 20 is sufficiently close 30 to maintain these parts in their assembled relation, as is clear from Figure 11.

By a similarly simple reverse procedure, the mentioned unitary assemblage of parts may be removed from within the tubular handle 20, the 35 blade carrier, together with its contained blades, slid off from the razor head stud 36, and the latter screwed into the socket 23, for mounting the razor head upon the razor handle 20 in position for use, as shown in Figures 1 to 4 inclusive. 40

As will be noted from Figure 11, the razor blade packages 43-43 are snugly contained within the blade carrier and are restrained against edge-wise shifting movement, by the side walls 40-40 of the blade carrier, as well as also by the stud 45 36. It is to be noted that the blade carrier side walls 40-40 protect the keen edges of the double-edged blades, such as 26, and particularly do so by preventing the edges of the blade packages 43-43 from coming into abutting contact 50 with the internal face of the tubular handle 20.

Heretofore, commonly, the edges of, either wrapped or unwrapped and bare, razor blades have not been so protected when housed within a tubular or otherwise hollow razor handle. 55

It is to be particularly noted, as is shown in Figure 11, that the described compact snugly housed assemblage of parts is positioned within the tubular handle 20 along three lines of abutting contact therewith. The substantially rectangular V-shaped corner of the cap element 25 provides one of these contact lines while the two external corners of the blade carrier provide the other two contact lines. These contact corners form substantially an equilateral triangle. 65

Thus, as is clearly evident from Figure 11, the disclosed blade carrier acts effectively as a filler member which holds the guard element 24 and the cap element 25 in closely assembled relation upon the interposed blade 26, and altogether prevents the possibility of the sharp edges of this blade coming into contact with the interior of the tubular handle 20, which it might do if the guard element 24 and the cap element 25 were allowed to become separated from each other. 70 75

It is evident that this important result will be similarly accomplished regardless of the particular rotative position of the described assemblage within the housing chamber formed within the 5 tubular handle member 20. It is also evident that the blade carrier, thus serving as a positioning member, will function equally well in this respect regardless of whether or not it contains any blade packages 43-43. Thus it may be advantageously so employed when empty, as a 10 valuable feature of my device.

The operation of the above described safety razor of my invention is as follows:

The operation and manner of use are largely 15 obvious from the preceding description taken in connection with the accompanying drawing.

It is to be noted that while the razor head construction itself has been improved, so as to stiffen and strengthen it, as well as also in other 20 respects, in the manner shown and above described, this improved razor head as a whole has been kept of appropriately narrow width and other dimensions which enable it, in its assembled condition, together with the blade-containing and protecting blade carrier integrated therewith into a single assemblage, to be housed as a unit within the internal chamber formed therefor within the tubular handle member 20, which is of no larger external size than the usual 25 safety razor handle not having this mentioned further function.

Thus with this unitary assemblage of mutually positioned parts housed within the closed tubular handle 20, there is presented a small and 30 exceedingly compact device. In this compact form the device may be easily slipped into a vest pocket, as well as also conveniently packed or stored within a very small available space. Also the device has an attractive and ornamental appearance, as will be in part evident from viewing 35 the handle portion only in Figure 1.

It has been found that the described narrow razor head, with the correspondingly narrow double-edged blade, operates as efficiently in use 40 as a usual form of safety razor having a wider head and using a wide blade.

The valuable attributes and advantages of the safety razor of my invention are now believed to have been made clearly evident.

50 The modified form of the razor blade carrier shown in Figure 12 is a further development and improvement in that element which may be advantageously employed, or it could be omitted, as in the razor blade carrier more particularly 55 shown in Figure 10.

The construction of the blade carrier shown in Figure 12 is similar to that first described, excepting as to one feature or element which has been embodied in this modified construction. It has 60 a flat rear wall 44, similar side walls 40-40, of which only one appears in Figure 12, similar in-turned slot-providing front flanges 41-41, one of which appears in Figure 12, and a similar end-closing flange 42 at one of its ends, while the back 65 wall 44 is similarly centrally provided with a circular aperture 39.

In this modified blade carrier, a resilient tongue 45 is struck forward from the rear wall 44. This tongue 45 normally, or in the empty condition of 70 the blade carrier shown in Figure 12, is disposed at an intermediate position, spaced inwardly or forwardly at its free end from the rear wall 44. This tongue 45 has a gradual forward and longitudinally inward inclination from a point in line 75 with the rear wall 44 adjacent to the open end

of the blade carrier toward a point at the free end of this tongue adjacent to the aperture 39, with the extreme free end portion of this tongue inwardly rounded or slightly bent back towards the rear wall 44, as clearly shown in Figure 12. 5

It will be understood that when the previously described blade carrier, shown in Figures 10 and 11, is completely filled with a fresh supply of blade packages 43-43, as shown in Figure 11, these packages will fit therein with sufficient friction not to fall out when the blade carrier is being handled in a detached condition thereof. However, after some of these packages 43-43 have been removed for the use of their contained blades, such as 26, the friction of the edges of 15 these packages with the opposed side walls 40-40 of the blade carrier may not be sufficient to prevent their dropping out, or at least becoming displaced toward and beyond the open end of the blade carrier. 20

In the blade carrier construction shown in Figure 12, the resilient tongue 45 will yield rearwardly substantially into alignment with the rear wall 44, so as to allow the blade carrier to be completely filled with blade packages, similarly as in 25 Figure 11. The spring tongue 45 will then press against the rearmost blade package near its center and will press all of the interposed blade packages, such as 43-43, forwardly into abutting and frictional engagement with the front flanges 30 41-41, as well as similarly with each other, while this tongue at the same time has resilient frictional abutting engagement with the rearmost blade package. 40

These blade packages 43-43 may be easily 35 withdrawn for use, one by one, or as many as desired, and the remaining fewer number of such packages left in the blade carrier, will be frictionally retained therein by the pressure of the tongue 45.

In other respects than mentioned, the operation of this blade carrier of Figure 12 is substantially the same as already described for the blade carrier shown in Figures 10 and 11, and its cooperative relation with other parts and features of 45 the complete device is substantially similar.

The modification shown in Figures 13 and 14 relates to the end flanges 37-37, shown in Figures 1 to 7 inclusive as provided upon the ends of the cap element 25. 50

The razor head of Figures 13 and 14 has a guard element 46 and a cap element 47. The latter is devoid of end guard flanges, while outwardly turned guard flanges 48-48 are carried respectively by the opposite ends of the guard element 46. In other respects the construction is similar to that previously described. 55

The cap element 47 of the razor head is interposed endwise between the guard flanges 48-48, in cooperative relation with the guard element 60 46, with a razor blade 26 interposed between and held in place by these two razor head elements. The outer ends of the guard flanges 48-48 are V-shaped, in conformity with the V-shaped outer side surface of the cap element 47, and are shown 65 as being substantially but not quite flush therewith.

The guard flanges 48-48 function in substantially the same manner as the first described guard flanges 37-37. The construction of Figures 13 and 14 has an advantage in that it can be manufactured more conveniently and economically. 70

It is obvious that various modifications may be made in the constructions shown in the drawing 75

and above particularly described, within the principle and scope of my invention as defined in the appended claims.

I do not specifically limit myself as to materials, size, shape, or a particular arrangement of parts, nor to minor features of construction and relationship of parts, as shown in the drawing and particularly described, these being given simply as a means for clearly describing the device of my invention.

What I claim is:—

1. In a safety razor, in combination, a tubular handle member, a razor head having a projecting stud by means of which it is adapted to be detachably mounted upon one end of said tubular handle member, a removable and replaceable closure for the other end of said handle member, and a blade carrier having an aperture through it by means of which it is adapted to be mounted upon said razor head in the detached condition of the latter with said razor-head stud passing through said aperture in said blade carrier to form a unitary assemblage adapted to be removably contained within said tubular handle member in the closed condition of the latter.

2. In a safety razor, in combination, a tubular handle member, a razor head having a projecting stud by means of which it is adapted to be detachably mounted upon one end of said tubular handle member, a removable and replaceable closure for the other end of said handle member, and a blade carrier having an aperture through it by means of which it is adapted to be mounted upon said razor head in the detached condition of the latter with said razor-head stud passing through said aperture in said blade carrier to form a unitary assemblage adapted to be removably contained within said tubular handle member in the closed condition of the latter, said tubular handle member and said unitary assemblage being relatively so dimensioned as to adapt said tubular handle member to retain said blade carrier upon said stud of said razor head within said tubular handle member.

3. In a safety razor, in combination, a tubular handle member, a razor head having a projecting stud by means of which it is adapted to be detachably mounted upon one end of said tubular handle member, a removable and replaceable closure for the other end of said handle member, a blade carrier having an aperture through it by means of which it is adapted to be mounted upon said razor head in the detached condition of the latter with said razor-head stud passing through said aperture in said blade carrier to form a unitary assemblage adapted to be removably contained within said tubular handle member in the closed condition of the latter, said tubular handle member and said unitary assemblage being relatively so dimensioned as to adapt said tubular handle to retain said blade carrier upon said stud of said razor head within said tubular handle member, and a razor-blade package which said blade carrier is adapted to carry, said blade package having an aperture through it through which said razor-head stud is adapted to pass and position said blade package relatively to said blade carrier.

4. In a safety razor, in combination, a tubular handle member, a closure for one end of said handle member provided outwardly with a screw-threaded socket, a removable and re-

placeable closure for the other end of said handle member, a guard element of a razor head, an outer cap element of the razor head cooperative with said guard element and adapted to hold in place an interposed razor blade, a screw-threaded stud rigidly extending from said cap element and adapted to pass freely through and beyond said razor blade and said guard element and screw into said socket for thus detachably mounting said razor head as a whole upon said handle member, and a blade carrier having an aperture through it adapted to pass freely over said stud beyond said guard element and form a unitary assemblage with said assembled razor head in the detached condition of the latter, said tubular handle member and said unitary assemblage being relatively proportioned to adapt said assemblage to be removably housed within said tubular handle member and to enable the latter then to maintain said blade carrier in place upon said stud.

5. In a safety razor, in combination, a tubular handle member, a closure for one end of said handle member provided outwardly with a screw-threaded socket, a removable and replaceable closure for the other end of said handle member, a guard element of a razor head, an outer cap element of the razor head cooperative with said guard element and adapted to hold in place an interposed razor blade, a screw-threaded stud rigidly extending from said cap element and adapted to pass freely through and beyond said razor blade and said guard element and screw into said socket for thus detachably mounting said razor head as a whole upon said handle member, a blade carrier having an aperture through it adapted to pass freely over said stud beyond said guard element and form a unitary assemblage with said assembled razor head, said tubular handle member and said unitary assemblage being relatively proportioned to adapt said assemblage to be removably housed within said tubular handle member and to enable the latter then to maintain said blade carrier in place upon said stud, and a predetermined number of razor-blade packages adapted to be removably carried by said blade carrier, each of said blade packages having an aperture through it adapted to pass freely over said stud by which said blade packages are thus positively positioned in said assemblage.

6. In a safety razor, in combination, a tubular handle member provided outwardly with a screw-threaded socket, a removable and replaceable closure for the other end of said handle member, an elongated guard element of a razor head having a flat under face adapted to be directed toward said handle member and having a central aperture through it, an outer cap element of the razor head cooperative with said guard element and adapted to hold in place an interposed razor blade having a central aperture through it adapted to register with said aperture in said guard element, a screw-threaded stud rigidly extending centrally from said cap element and adapted to pass freely through said central apertures in said razor blade and said guard element and screw into said socket for thus detachably mounting said razor head as a whole upon said handle member, and an elongated flattened blade carrier adapted to abut flatwise against said flat face of said guard element, said blade carrier comprising opposed front and rear flat walls and opposed side walls connecting said front and rear walls together.

and having a central aperture through it flatwise adapted to pass freely over said cap element stud beyond said guard element thereby to form a single unitary assemblage with said assembled 5 razor head in the detached condition of the latter, said tubular handle member and said unitary assemblage being relatively proportioned to adapt said assemblage to be removably housed within said tubular handle member and to enable the latter then to maintain said blade carrier in place upon said stud.

7. In a safety razor, in combination, a tubular handle member provided outwardly with a screw-threaded socket, a removable and replaceable 15 closure for the other end of said handle member, an elongated guard element of a razor head having a flat under face adapted to be directed toward said handle member and having a central aperture through it, an outer cap element 20 of the razor head cooperative with said guard element and adapted to hold in place an interposed razor blade having a central aperture through it adapted to register with said aperture in said guard element, a screw-threaded stud rigidly extending centrally from said cap element and adapted to pass freely through said central apertures in said razor blade and said guard element and screw into said socket for thus detachably mounting said razor head as a 25 whole upon said handle member, an elongated flattened blade carrier adapted to abut flatwise against said flat face of said guard element, said blade carrier comprising opposed front and rear 30 flat walls and opposed side walls connecting said front and rear walls together and having a central aperture through it flatwise adapted to pass freely over said cap element stud beyond said guard element thereby to form a single unitary assemblage with said assembled razor head in 35 the detached condition of the latter, said tubular handle member and said unitary assemblage being relatively proportioned to adapt said assemblage to be removably housed within said tubular handle member and to enable the latter then to maintain said blade carrier in place upon said stud, and a predetermined number or blade packages 40 adapted to be removably contained within said blade carrier, each of said blade packages being provided with a central aperture through it in alignment with said aperture of said blade carrier and through which said cap element stud is adapted to pass and thereby positively retain 45 said blade packages within said blade carrier.

8. In a safety razor, in combination, a tubular handle member provided outwardly with a screw-threaded socket, a removable and replaceable 55 closure for the other end of said handle member, an elongated guard element of a razor head having a flat under face adapted to be directed toward 60 said handle member and having a central aperture through it, lugs rigidly projecting from the other face of said guard element at opposite sides of said aperture in alignment therewith longitudinally of said guard element, an outer cap element of the razor head cooperative with said guard element and adapted to hold in place an interposed razor blade having apertures through it adapted to pass over said lugs and a central 65 aperture adapted to register with said aperture in said guard element, a screw-threaded stud rigidly extending centrally from said cap element and adapted to pass freely through said central apertures in said razor blade and said guard element and screw into said socket for thus detachably mounting said razor head as a 70 whole upon said handle member, said cap element being transversely outwardly V-shaped and provided along its inner side with a right-angled groove extending at opposite sides of its said stud and adapted to receive therein said guard 75 element lugs, an elongated flattened blade carrier having a flat face adapted to abut against said flat face of said guard element and having a central aperture through it flatwise adapted to pass freely over said cap element stud beyond said guard element thereby to form a single unitary assemblage with said assembled razor head in the detached condition of the latter, said tubular handle member and said unitary assemblage being relatively proportioned to adapt said assemblage to be removably housed within said tubular handle member and to enable the latter then to maintain said blade carrier in place upon said stud, said blade carrier comprising opposed front and rear flat walls and opposed side walls connecting said front and rear walls together, and a predetermined number of blade packages adapted to be removably contained within said blade carrier, each of said blade packages being provided with a central aperture through it in alignment with said aperture of said blade carrier and through which said cap element stud is adapted to pass and thereby positively retain said blade packages within said blade carrier.

9. In a safety razor, in combination, a tubular handle member provided outwardly with a screw-threaded socket, a removable and replaceable closure for the other end of said handle member, an elongated guard element of a razor head having a flat under face adapted to be directed toward said handle member and having a central aperture through it, lugs rigidly projecting from the other face of said guard element at opposite sides of said aperture in alignment therewith longitudinally of said guard element, an outer cap element of the razor head cooperative with said guard element and adapted to hold in place an interposed razor blade having apertures through it adapted to pass over said lugs and a central aperture adapted to register with said aperture in said guard element, a screw-threaded stud rigidly extending centrally from said cap element and adapted to pass freely through said central apertures in said razor blade and said guard element and screw into said socket for thus detachably mounting said razor head as a whole upon said handle member, said cap element being adapted to receive therein said guard element lugs, and an elongated flattened blade carrier adapted to abut flatwise against said flat face of said guard element, said blade carrier comprising opposed front and rear flat walls and opposed side walls connecting said front and rear walls together and having a central aperture through it flatwise adapted to pass freely over said cap element stud beyond said guard element 10 thereby to form a single unitary assemblage with said assembled razor head in the detached condition of the latter, said tubular handle member and said unitary assemblage being relatively proportioned to adapt said assemblage to be removably housed within said tubular handle member and to enable the latter then to maintain said blade carrier in place upon said stud.

10. In a safety razor, in combination, a tubular handle member provided outwardly with a screw-threaded socket, a removable and replaceable closure for the other end of said handle member, an elongated guard element of a razor head having a flat under face adapted to be directed toward said handle member and having a central aperture through it, lugs rigidly projecting from the other face of said guard element at opposite sides of said aperture in alignment therewith longitudinally of said guard element, an outer cap element of the razor head cooperative with said guard element and adapted to hold in place an interposed razor blade having apertures through it adapted to pass over said lugs and a central aperture adapted to register with said aperture in said guard element, a screw-threaded stud rigidly extending centrally from said cap element and adapted to pass freely through said central apertures in said razor blade and said guard element and screw into said socket for thus detachably mounting said razor head as a whole upon said handle member, said cap element being transversely outwardly V-shaped and provided along its inner side with a right-angled groove extending at opposite sides of its said stud and adapted to receive therein said guard element lugs, an elongated flattened blade carrier having a flat face adapted to abut against said flat face of said guard element and having a central aperture through it flatwise adapted to pass freely over said cap element stud beyond said guard element thereby to form a single unitary assemblage with said assembled razor head in the detached condition of the latter, said tubular handle member and said unitary assemblage being relatively proportioned to adapt said assemblage to be removably housed within said tubular handle member and to enable the latter then to maintain said blade carrier in place upon said stud, said blade carrier comprising opposed front and rear flat walls and opposed side walls connecting said front and rear walls together, and a predetermined number of blade packages adapted to be removably contained within said blade carrier, each of said blade packages being provided with a central aperture through it in alignment with said aperture of said blade carrier and through which said cap element stud is adapted to pass and thereby positively retain said blade packages within said blade carrier.

11. In a safety razor, in combination, a tubular handle member, a razor head having a projecting stud by means of which it is adapted to be detachably mounted upon one end of said tubular handle member, a removable and replaceable closure for the other end of said handle member, 75

and a blade carrier having an aperture through it by means of which it is adapted to be mounted upon said razor head in the detached condition of the latter with said razor-head stud passing through said aperture in said blade carrier to form a unitary assemblage adapted to be removably contained within said tubular handle member in the closed condition of the latter, said blade carrier being of elongated flattened box-like form comprising opposed front and rear walls, opposed side walls connecting said front and rear walls together, and an end-closing wall at one end only of said blade carrier.

11. In a safety razor, in combination, a tubular handle member, a razor head having a projecting stud by means of which it is adapted to be detachably mounted upon one end of said tubular handle member, a removable and replaceable closure for the other end of said handle member, a blade carrier having an aperture through it by means of which it is adapted to be mounted upon said razor head in the detached condition of the latter with said razor-head stud passing through said aperture in said blade carrier to form a unitary assemblage adapted to be removably contained within said tubular handle member in the closed condition of the latter, said tubular handle member and said unitary assemblage being relatively so dimensioned as to adapt said tubular handle member to retain said blade carrier upon said stud of said razor head within said tubular handle member, and a razor-blade package which said blade carrier is adapted to carry, said blade package having an aperture through it through which said razor-head stud is adapted to pass and position said blade package relatively to said blade carrier, said blade carrier being of elongated flattened box-like form comprising opposed front and rear walls, a resilient blade-holding tongue fixedly carried at one of its ends by one of said walls and extending into the space between said walls, and opposed side walls connecting said front and rear walls together.

12. In a safety razor, in combination, a tubular handle member, a closure for one end of said handle member, a removable and replaceable closure for the other end of said handle member, one of said closures being provided outwardly with a screw-threaded socket, a guard element of a razor head having a central aperture through it, an outer cap element of the razor head adapted to be assembled with said guard element to form a razor head adapted to carry an interposed razor blade having a central aperture through it adapted to register with said aperture in said guard element, a screw-threaded stud rigidly extending centrally from said cap element and adapted to pass freely through said central apertures in said razor blade and said guard element and screw into said socket for thus detachably mounting said assembled blade-carrying razor head as a whole upon said handle member, and a filler member having an aperture through it adapted to pass over said stud into abutment with said guard element and form a single unitary assemblage with said assembled blade-carrying razor head in the detached condition of the latter, said tubular handle member and said unitary assemblage being relatively proportioned to adapt said assemblage to be removably housed within said tubular handle member and to engage with said cap element and said filler member thereby to maintain said guard element and said cap element in compactly assembled relation upon said interposed razor blade.

thus to maintain the sharp edges of the latter out of contact with the inner surface of the said tubular handle member.

13. In a safety razor, in combination, a tubular handle member, a closure for one end of said handle member, a removable and replaceable closure for the other end of said handle member, one of said closures being provided outwardly with a screw-threaded socket, a guard element of a razor head having a central aperture through it, an outer cap element of the razor head adapted to be assembled with said guard element to form a razor head adapted to carry an interposed razor blade having a central aperture through it adapted to register with said aperture in said guard element, a screw-threaded stud rigidly extending centrally from said cap element and adapted to pass freely through said central apertures in said razor blade and said guard element and screw into said socket for thus detachably mounting said assembled blade-carrying razor head as a whole upon said handle member, and a filler member having an aperture through it adapted to pass over said stud into abutment with said guard element and form a single unitary assemblage with said assembled blade-carrying razor head in the detached condition of the latter, said cap element having an outwardly V-shaped portion along its length and said filler member having external corner portions along its length disposed in triangular relation with said outwardly V-shaped portion of said cap element, said tubular handle member and said unitary assemblage being relatively proportioned to adapt said assemblage to be removably housed within said tubular handle member with the latter then in engagement with said V-shaped portion of said cap element and with said corner portions of said filler element thereby to maintain said razor head in closely assembled relation with said razor blade and thus to maintain the sharp edges of said razor blade out of contact with the inner surface of said tubular handle member.

14. In a safety razor, in combination, an elongated guard element of a razor head having a flat under face and having a central aperture through it, an outer cap element of the razor head cooperative with said guard element and adapted to hold in place an interposed razor blade having a central aperture through it adapted to register with said aperture in said guard element, an attaching stud rigidly extending centrally from said cap element and adapted to pass freely through said central apertures in said razor blade and said guard element and extend beyond said flat face of the latter, and an elongated flattened blade-package carrier adapted to abut flatwise against said flat face of said guard element, said carrier comprising opposed front and rear flat parallel walls and opposed flat parallel side walls connecting said front and rear walls together and having a central aperture through it flatwise adapted to pass freely over said cap element stud beyond said guard element thereby to form a single unitary assemblage with said assembled razor head in the detached condition of the latter and to be positioned thereon by means of said stud.

15. In a safety razor, in combination, an elongated guard element of a razor head having a flat under face and having a central aperture through it, an outer cap element of the razor head cooperative with said guard element and adapted to hold in place an interposed razor blade having a central aperture through it adapted to register

with said aperture in said guard element, an attaching stud rigidly extending centrally from said cap element and adapted to pass freely through said central apertures in said razor blade and said guard element and extend beyond said flat face of the latter; an elongated flattened blade-package carrier adapted to abut flatwise against said flat face of said guard element, said carrier comprising opposed front and rear flat parallel walls and opposed flat parallel side walls connecting said front and rear walls together and having a central aperture through it flatwise adapted to pass freely over said cap element stud beyond said guard element thereby to form a single unitary assemblage with said assembled razor head in the detached condition of the latter and to be positioned thereon by means of said stud, and a predetermined number of blade packages adapted to be removably contained within said blade-package carrier, each of said blade packages being provided with a central aperture through it in alignment with said aperture of said blade-package carrier and through which said cap element stud is adapted to pass and thereby positively retain said blade packages

within said blade-package carrier in said unitary assemblage.

16. In a safety razor, in combination, a razor-head having a projecting attaching stud, a blade carrier having an aperture through it by means of which it is adapted to be mounted upon said razor head in a detached condition of the latter with said razor-head stud passing through said aperture in said blade carrier to form a unitary assemblage in which said blade carrier is positioned upon said razor head by means of said stud, and a razor-blade package which said blade carrier is adapted to carry, said blade package having an aperture through it through which said razor-head stud is adapted to pass and position said blade package relatively to said blade carrier and razor head, said blade package carrier being of elongated flattened box-like form comprising opposed front and rear flat parallel walls and opposed flat parallel side walls connecting said front and rear walls together, and a resilient frictionally-acting-blade-package-holding tongue fixedly carried at one of its ends by said rear wall and yieldably extending into the space within said blade-package carrier between said front and rear walls.

SIDNEY H. BENJAMIN.
